UNITED STATES PATENT OFFICE.

SIGMUND STERNAU, OF NEW YORK, N. Y.

DESIGN FOR A KETTLE-STAND.

SPECIFICATION forming part of Design No. 23,765, dated November 6, 1894.

Application filed October 6, 1894. Serial No. 525,170. Term of patent 3½ years.

To all whom it may concern:

Be it known that I, SIGMUND STERNAU, a citizen of the United States, residing in New York, county of New York, and State of New York, have invented and produced a new and original Design for Kettle-Stands, of which the following is a specification, reference being had to the accompanying drawing, which shows the stand in perspective.

The leading feature of my design is the solid base circular in form, having projecting upwardly therefrom the two open work standards.

A is the base of the stand, bent in cross

section, as shown, and circular in its general 15 contour, and from which extend the legs or supports a.

B represents standards of fanciful skeleton design; and having their upper ends b waved or curved as shown.

What I claim is—

The design for a kettle stand as hereinabove shown and described.

SIGMUND STERNAU.
